UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed February 24, 1925. Serial No. 11,182.

- My invention relates to rail anchoring devices and has for its object to provide an improved one-piece rail anchor device which is so formed as to provide a firm grip on the rail base, which will be easy of application, and which will provide a relatively large surface adapted to bear against one of the vertical faces of a cross tie.
- A more specific object is to provide a one-piece rail anchor formed at one end with a jaw portion of such configuration as to grip one surface of a rail base adjacent the edge of the rail at one side thereof, and to grip another surface of said base at a point between said edge and the center of the base and formed at the other end with a portion which is flexed outwardly so as to snap over the edge of the rail base at the opposite side of the rail.
- Another specific object is to provide a rail anchor made of a spring bar which is flexed vertically of the rail during its application thereto to effect a grip on the upper and lower surfaces of the rail base at one side of the rail and which is flexed laterally of the rail base to effect a spring grip on opposite edges of the rail.
- The invention has for a further object such other new and improved constructions, relating to rail anchoring devices, as will be hereinafter described and claimed for carrying out the above stated objects and such other incidental objects as will appear from the description of the embodiment of my invention shown in the accompanying drawing.
- In the drawing
- Fig. 1 is a plan view of the base flange of a railroad rail showing a preferred embodiment of my invention applied in its operative position on the rail.
- Fig. 2 is a cross-sectional view of a rail showing my improved rail anchor in its initial position on the base flange of a rail and before the device is flexed to its normal gripping position on the rail.
- Fig. 3 is a view similar to Fig. 2 showing the rail anchor in its normal operative position, and
- Fig. 4 is a view, in perspective, of the anchor device.
- Referring to the drawing, 10 designates a railroad rail supported on a cross tie 11, and 12 indicates one embodiment of my improved anchor device applied to the rail so as to grip the rail base 13 in a position to bear against a vertical face of the cross tie whereby any tendency that the rail may have to move longitudinally is resisted.
- The embodiment of the invention shown in the drawing consists preferably of a relatively heavy steel bar formed at one end with a hook-shaped jaw portion 14 adapted to grip one flange of the rail base 13 and formed at the other end with an upstanding arm 15 which engages the other edge of the rail base.
- The jaw portion 14 includes a part 16 for engaging the vertical surface 17 of the rail base, an angularly disposed end portion 18 for engaging the upper surface of the rail base, and a bearing 19 adapted to bear against the bottom surface of the rail at a point intermediate the edge and the longitudinal center of the base. The end portion 18 preferably extends at an angle to the inclined upper surface of the rail base so as to confine its engagement with the upper corner thereof. The bearing portion 19 is formed by bending the bar to a substantially V-shaped configuration so as to provide a point of engagement with clearance 20, 20^a, between the rail base and the anchor, on opposite sides of the bearing 19. The other end of the bar is bent downwardly and upwardly to provide the upstanding arm 15 and at the same time provides a tie abutting portion 21 which will bear against the vertical face of a cross tie at a substantial distance below the bottom surface of the rail base. The arm 15 is formed with a notch 22 adapted to fit over the edge of the rail base on the side opposite to that engaged by the jaw portion 14. The arm 15 is preferably formed so that the distance between the face 23 of the jaw and the face 24 of the notch 22 is normally less than the width of the rail base to which the anchor is intended to be applied, and so that it is necessary, in applying the anchor, to flex the arm 15 outwardly with respect to the edge 25 of the rail base. In order to facilitate the flexing of the arm 15, its upper end is preferably curved outwardly to provide a cam surface 26 which, when the anchor is raised, bears against the edge 25 of the rail base, so as to flex the arm outwardly.
- In applying the anchor to a rail, the hook-shaped jaw portion 14 is hooked over the edge 23 of the rail base and the other

end is swung upwardly until the anchor assumes the position shown in Fig. 2. This swinging movement of the anchor about an axis extending longitudinally of the rail 5 brings the end 18 of the jaw into engagement with the upper corner of the rail base and the bearing portion 19 into engagement with the rail base at a point between the longitudinal edge and the center of the base. 10 Further upward movement of the arm 15, it will be seen, will stress the jaw portion 14 of the anchor so that it will exert a firm spring grip on the upper and lower surfaces of the rail base, the arm 15 as previously 15 described, being positioned so that the distance between the face 23 of the jaw 14 and the face 24 of the notch 22 is less than the width of the rail base, will be forced outwardly with respect to the edge 25 of the rail 20 base until the notched portion snaps over this edge of the rail base. In this position of the anchor the jaw portion 14, being tensioned by the upward swinging movement of the arm 15, exerts vertical pressure on the 25 upper and lower surface of the rail base and the outward flexing of the arm 15 produces a spring gripping action transversely of the rail on opposite edges of the rail base.

While I have described my invention in 30 connection with one specific embodiment, it will be obvious that modifications in structures might be made without departure from the invention. It will therefore be understood that I contemplate all such modifications in structure as come within the scope 35 of the appended claims.

I claim:

1. A rail anchor comprising a member 40 formed with a portion adapted to be moved into gripping engagement with the base flange of a rail at one side of the rail by a swinging movement about an axis extending longitudinally of the rail and formed with an upstanding portion provided at its 45 upper end with a recess adapted to engage with the base flange at the other side of the rail to hold the first mentioned portion in its gripping position.

2. A rail anchor comprising a member 50 formed at one end with a portion adapted to be moved into gripping engagement with the base flange of a rail at one side of the rail by a swinging movement about an axis extending longitudinally of the rail and 55 formed at the other end with an upstanding spring arm provided near its upper end with a shoulder for engagement with one longitudinal corner of the base flange at the other side of the rail to hold the first mentioned portion in its gripping position.

3. A rail anchor comprising a member 60 formed at one end with a portion adapted to be moved into gripping engagement with the base flange of a rail at one side of the rail by a swinging movement about an axis 65

extending longitudinally of the rail and formed at the other end with an upstanding spring arm adapted to bear against a cross tie and adapted to snap into engagement with the base flange at the other side of the rail to hold the first mentioned portion in its gripping position. 70

4. A rail anchor comprising a member 75 formed at one end with a portion adapted to be moved into gripping engagement with the upper and lower surfaces of the base flange of a rail at one side of the rail by a swinging movement about an axis extending longitudinally of the rail and formed at the other end with a spring arm which bears 80 against a cross-tie and formed at its end with means for engagement with the base flange of the other side of the rail to hold the first mentioned portion in its gripping position. 85

5. A rail anchor comprising a member 90 formed at one end with a hook-shaped portion adapted to grip one face of a rail base but which confines its said engagement to a point adjacent the longitudinal edge of said base and which engages the opposite face of the base at a point intermediate said first mentioned point of engagement and the longitudinal center of the base and formed at the other end with a portion adapted to be flexed upwardly and outwardly with respect to the edge of the base flange at the opposite side of the rail and to snap into gripping engagement therewith to hold the first mentioned portion in its gripping position on the rail and to exert a spring grip transversely of the rail on opposite edges of the rail base. 95

6. A rail anchor comprising a bar formed at one end with a jaw portion adapted to engage the upper, lower and vertical surfaces of a rail base at one side of a rail and formed at the other end with an upstanding portion adapted to bear against the vertical surface of the base flange at the other side of the rail, said jaw portion and said upstanding portion being so disposed with relation to each other as to require distortion of the anchor to force said upstanding portion to its normal operative position, whereby said jaw portion is tensioned to effect a spring grip on the upper and lower surfaces of the rail base and the upstanding end portion is tensioned to effect a spring grip transversely of the rail on opposite edges of the rail base. 105 110 115

7. A rail anchor comprising a bar formed at one end with a jaw portion adapted to engage the upper, lower and vertical surfaces of a rail base at one side of the rail, and formed at the other end with an upstanding portion adapted to bear against the vertical surface of the base flange at the other side of the rail; the distance between the surfaces of the anchor for engaging the opposite edges of the rail base being normally less 120 125 130

than the width of the rail, whereby the said upstanding portion is flexed outwardly during the application of the anchor to its operative position on the rail.

5 8. A rail anchor comprising a bar formed at one end with a jaw portion adapted to be moved into gripping engagement with the top and bottom surfaces of the base flange of a rail at one side thereof and formed at 10 the other end with an upstanding portion for bearing against an adjacent cross-tie and adapted to grip the opposite edge of the rail base, the said gripping portions being so disposed with relation to each other as to 15 require an outward flexing of the upstanding portion during the application of the device to a rail, and the said upstanding portion being formed with a cam surface which rides over the edge of the rail base during said 20 flexing movement.

9. A rail anchor comprising a bar formed at one end with a jaw portion for engaging

the upper corner only of the top surface of the flange, engages the under surface of the rail base and is adapted to be moved to its 25 gripping position by a swinging movement about an axis extending longitudinally of the rail and formed at the other end with an upstanding portion adapted to grip the opposite edge of the rail base, the said rail 30 gripping portions being so disposed with relation to each other as to require an outward flexing of the upstanding portion during the application of the device to a rail.

10. A rail anchor comprising a bar formed 35 at one end with a jaw portion adapted to engage the top, bottom and vertical surfaces of a rail base at one side of the rail and formed at the other end with an upstanding portion having a recess to receive the other edge of 40 the rail and adapted to snap into locking engagement with the rail base.

HAROLD G. WARR.
